SHIPPING CRATE FOR LATRINE FIXTURES CONVERTIBLE INTO COMPLEMENTARY LATRINE STRUCTURE

Frederick T. Sheffield, Alexandria, Va., assignor to Wm. H. Singleton Co., Inc., Arlington, Va., a corporation of Virginia

Application February 3, 1953, Serial No. 334,852

5 Claims. (Cl. 20—2)

This invention relates to a shipping crate for latrine fixtures, convertible into the standing partitions, floor and roof of field latrine structure.

The invention is particularly applicable to use by the military services, and has for its object the provision of a shipping crate and the complement of plumbing fixtures and sized and threaded piping for furnishing a field latrine, the crate being convertible into a definite pattern of latrine structure including an open ended, roofed and floored shower stall providing support on the outer face of one side for the flush tanks of a row of water closets, having privacy wings projecting outwardly from the ends of said side flanking the row of water closets, the opposite side of said shower stall having a longitudinal extension in the plane of said opposite side, said opposite side including said extension, providing an outer face of sufficient length to afford back support for a row of lavatory basins, the conversion being accomplished without any modification of the component parts of the crate or the necessity of drilling holes or measuring to determine the location of any of the parts.

More specifically stated, the object of the invention is to provide a convertible shipping crate for the purpose described, having the side panels and the top and end panels permanently put together so that in the conversion the unit formed by these panels may be kept intact, constituting the shower stall of which the top panel forms the roof and the bottom panel the floor, the end panels of the crate being bolted to the side panels so that they can be readily removed, one end panel being a single member forming the extension of one side of the shower stall, and the other end panel being transversely divided into upper and lower sections which become the privacy wings in the conversion, existing bolt holes in the crate and the bolts of the crate being employed in integrating the latrine structure.

Other objects of the invention will appear as the following description of a practical embodiment thereof proceeds.

In the drawings which accompany and form a part of the following specification, and throughout the figures of which the same reference characters have been employed to designate identical parts:

Figure 1 is a side elevation of a shipping crate embodying the principles of the invention;

Figure 2 is an end elevation viewed from the left in Figure 1;

Figure 3 is an end elevation viewed from the right in Figure 1;

Figure 4 is a perspective view of the latrine structure made up from the crate components, viewed from the side adjacent the water closets;

Figure 5 is a perspective view of the latrine structure viewed from the side contiguous to the lavatory basins;

Figure 6 is a cross-section taken along the line 6—6 of Figure 5;

Figure 7 is a side elevation of the crate viewed from the side opposite that of Figure 1;

2

Figure 8 is a perspective view of the shower pan.

Referring now in detail to the several figures, and first to Figures 1, 2, 3 and 7 which illustrate the crate construction, the crate is formed of two side panels A and B, and two end panels C and D, the end panel C being transversely divided into sections E and F of equal height. There is a bottom panel G and a top panel H. Letters have been used to designate as a whole these components of the crate so as the better to identify them in the figures showing the latrine conversion.

The side panels A and B each comprise a frame of dressed 2" x 4" material consisting of top and bottom members 1 and 2 and side members 3 and 4 suitably secured together and defining the peripheries of the respective panels, which are congruent. Three intermediate studs 5, 6 and 7 extend between the top and bottom members, being preferably equidistantly spaced from each other and from the side members 3 and 4. The side panel A which is to serve as a backing for the lavatory basins in the conversion is provided with a longitudinal member 8 in sections, occupying the spaces between the studs and between the side members and adjacent studs at such level as to afford an anchorage for the fastening means which secure the lavatory basins to the panel. The opposite side panel B is provided with a similar longitudinal member 9 at such level as to serve as an anchorage for the securing means of the flush tanks, in the conversion. The frame members are arranged with their longer width dimensions extending outwardly. The frames are sheathed on one side with $\frac{3}{4}$ " boards 10, running longitudinally, the sheathed sides of the side panels being on the inside of the crate as well as on the inside of the shower stall in the conversion.

The bottom panel G comprises two spaced skids 11 and 12 on which are laid crosswise the relatively heavy floor boards 13. The skids are undercut at their ends to form rabbets 14 and 15, the purpose of which is to allow room for slings to be arranged beneath the crate at its ends for purpose of transportation, also to allow a prying tool to be inserted for shifting the shower stall in proper position with respect to the preformed concrete slab on which it is to be finally positioned.

The floor panel is permanently secured to the side panels by suitable fastening means, not shown, extending through the bottom frame members 2 and through the board floor into the skids.

The roof panel comprises three transverse channel irons bridging the side members at the top, and being permanently secured thereto. The spaces between the channel irons are sheathed with $\frac{3}{4}$ " boards 17, the boards being secured to the side members by fastening means, not shown, through said boards and through the top frame members 1. The overall height of the unit thus described is 7' and its overall width 3' 2 $\frac{1}{4}$ '. This provides for head room in the shower stall and ample lateral space for the persons taking the shower. Extending widthwise across the floor panel at the ends and between the sheathed sides of the side panels are 2 x 4 members 18 and 19. These form door sills for the shower stall. The longer width dimensions of the members 18 and 19 extend upwardly. A shower pan 20, shown in Figure 7, is preferably packed in the crate in the permanent position which it will occupy in the conversion. It is rectangular in shape, having upstanding sides 21 and 22 and upstanding ends 23 and 24, the latter being of the same height as the members 18 and 19, and being bent outwardly at their top edges to form the flanges 25 and 26 of the same width as the members 18 and 19. The shower pan is nested in the bottom of the crate, having its sides snugly fitting against the sheathed sides of the side panels, having its ends against the inner faces of the members 18 and 19, and having the flanges 25 and

26 overlying the members 18 and 19, and resting thereupon. The shower pan has a drainage fixture 27 in the middle and a registering aperture 28 is formed in one of the floor boards 13 to permit the drainage fixture to be connected to suitable plumbing exposed in the slab.

Referring now to the end panel C, its overall height is the distance between the upper level of the top panel H and the level of the under surface 29 of the rabbet 15. Thus, when the panel C is bolted in place, as shown in Figure 1, the bottom of said panel forms a continuation of the under surface of said rabbet. The panel C is divided transversely into identical sections E and F, each of which consists of a frame made of dressed 2" x 4" material comprising top and bottom members 30 and 31, side members 32 and 33, and intermediate vertical studs 34, all suitably secured together. One of the side members of each section, the right member 33, as shown in Figure 2, is of double thickness, constituted by two 2" x 4"'s placed in side by side contiguity, giving this side member a substantially square cross-section. The reason for this is that in the conversion each section will be perpendicularly outwardly offset relative to the relative ends of the side wall B, as best shown in Figures 5 and 6, and for the sake of rigidity it is desirable to have the members 33 abut the adjacent respective side members 3 and 4 of the side panel B throughout the full width of said side members.

In the crate, the adjacent top and bottom members 30 and 31 of the sections E and F are in contact. Both sections are sheathed on their inner sides by 3/4" boards 35. All frame members of these sections are arranged with their longer width dimensions extending outwardly.

The pattern of bolt holes through both sides of both sections is identical, the corresponding right and left bolt holes being equally spaced from the bottoms of the sections, and it is important that the bolt holes 36 and 37 through the lower half of the frame member 4 of panel B, which provide for the securing of the end panel D, be identical, in their spacing from the floor panel, to the bolt holes 38 and 39 in the frame member 3 of panel B which register with the corresponding bolt holes in section F. Thus, in the conversion, when sections E and F are placed in offset relation to the panel B with their side members 33 against the respective ends of panel B, the bolt holes in the members 33 will register respectively with the lower pair of bolt holes in the side members 3 and 4 of panel B. The bolts are a free fit in the bolt holes for easy insertion and withdrawal, and four of the bolts employed in securing sections E and F to the crate are used in bolting these sections to the frame members 3 and 4 of panel B. The heads of the bolts through the side members 33 of sections E and F are countersunk, as shown at 40 in Figure 1, so that in the conversion a lining of tempered Masonite or the like will lie flat against the outside of sections E and F, as shown in Figures 4 and 5 at 41.

Now proceeding to a description of the one piece end panel D, this is similar to the other panels to the extent that it comprises a frame of 2" x 4" material consisting of top and bottom members 42 and 43, side members 44 and 45, and an intermediate stud 46, all suitably secured, and it has also the sectional cross member 47 extending between the stud and side members. The cross member 47, however, is at such a height as to be level with the longitudinal member 8 when the crate components are assembled in the conversion. Thus it becomes a rectilinear extension of the member 8 at a proper height to receive the securing means for one of the lavatory basins. The panel D, like the rest of the panels, is sheathed on its inner side with 3/4" boards, those of panel D being designated by the numeral 48. The frame members of panel D are positioned with their longer width dimensions extending outwardly.

Since the panel D is to be assembled, in the conversion, in the plane of the side panel A, with its side mem-

ber 44 in abutment with either of the side members 3 or 4 of the side panel A, the bolts which secure these components must be axially parallel with the plane of the panel A. This requires the provision of four additional bolt holes 49, passing through the side member 44 of panel D perpendicular to the bolt holes 50 in said side member which receive the bolts that secure the panel D to the crate.

In order to avoid weakening the side member 44 of panel D by having the conversion bolt holes 49 intersect the crate bolt holes 50 in the same cross-sectional planes, the former bolt holes are positioned slightly above the crate bolt holes 50, as shown in Figures 1 and 3, and so spaced from the under faces 51 of the rabbets 14 of the skids that when the end panel D is secured in place in the conversion, its bottom edge will be flush with said under faces. Consequently, when the end panel D is secured to the crate by bolts through the holes 50, its bottom edge will be above the plane of said under faces by an amount equal to the difference in level between the axes of the bolt holes 49 and 50, this being indicated at 52 in Figure 3.

The overall length of the crate, as shown, is 7' 1", the inside length being 6' 4", which is also the length of the shower stall. A crate of this size will contain three water closets 53, including the flush tanks 53', three lavatory basins 54, including the supporting frames, the shower pan 20, one urinal trough 55, rods and curtains 56 and 57 for the ends of the shower stall, a water heating unit, not shown, including a burner and stack sections, the smaller fixtures such as the soap dishes 58, drinking font 59 and shower heads, bibbs, etc., not shown, and the necessary piping and plumbing connections, not shown, the piping being in sized and threaded pieces, the above being the complement to fit the urinal structure provided by the crate components. The packing of the equipment requires the employment of several temporary partitions which are not shown, since they play no part in the conversion. The crate also contains sufficient sheet material, such as tempered Masonite, to line both sides of each of the vertical panels in the conversion, and the exposed edge faces of each. The sheet material is pre-cut in pieces which when fitted together form areas congruent with the faces of the panels which they are designed to line, thus obviating the necessity for any cutting to be done in the field. The crate will also contain a set of three wooden feet 61 for supporting the outer ends of the panels D, E, and F in the conversion. These feet will be drilled and counterbored for lag screws, not shown, by means of which the feet are secured to the respective panels.

Referring now to Figures 4, 5 and 6, the several panels of the urinal structure are identified by the same letters which designate the corresponding crate components. The panels in the conversion are shown lined with sheets of tempered Masonite 60. It will be noted from Figure 6 that the sheathed sides of the panels A and B are on the inside of the shower stall, affording a firm support for the contiguous lining 60, against which the men may lean while taking a shower, and that the lining overlaps the side edges of the shower pan, avoiding seepage of water between the shower pan and the enclosing structure.

The urinal unit, as described, is designed to serve fifty men. It will generally be in a roofed building with other like units, so that no provision is necessary for a waterproof roof lining.

It is contemplated that prior to the installing of the urinal, a level slab of concrete will have been prepared with soil pipe and water drainage connections projecting from its upper face in a predetermined pattern of spacing to correspond with the plan of the urinal, the latter being erected on said slab. In disassembling the crate and reassembling the urinal structure, no cutting, measuring, drilling, or other expert work is required,

so that the conversion may be readily made by unskilled personnel and by the use solely of a wrench, except that the lining sheets are nailed in place.

While I have in the above description disclosed a practical embodiment of the invention, it will be understood by those skilled in the art that the specific details of construction, arrangement of parts and dimensions, as disclosed, are by way of example and not to be construed as limiting the scope of the invention.

What I claim is:

1. In a demountable shipping crate for latrine fixtures convertible into latrine structure complementary to said fixtures, the components of which crate comprise an intact intermediate section consisting of congruent, spaced opposite side panels, a top panel and a bottom panel bridging said side panels and secured thereto, a single unit end panel closing one end of said intermediate section, an end panel closing the opposite end of said intermediate section transversely divided into two end sections of the same size and shape, said side panels, single unit end panel and said end sections each comprising a peripheral frame on the outside consisting of top, bottom and side members, said frame members being of rectangular cross-section, said frames being sheathed on their inner sides, the side frame members at one side of each of said end sections being coextensive in width with the face which they overlie of the adjacent side frame member of the adjacent side panel, said single unit end panel and said end sections being detachably secured to said intermediate section by bolts through registering bolt holes in said end panel and end sections and in said adjacent side frame members of the side panels, the transversely corresponding bolt holes in each of said end sections being equally spaced from the bottoms of the respective sections, and pattern of spacing being identical in each section and being identical with the pattern of spacing of the bolt holes in the lower half of the single unit end panel.

2. Group of correlated structural components adapted to be assembled alternatively to form a shipping crate for latrine fixtures and a latrine for incorporating said fixtures, said group comprising a rectangular tunnel including side panels, a top panel and a bottom panel, forming, in the crate, the intermediate part between the ends, and in the latrine an open ended shower stall;

a single unit panel forming one end closure of the crate, and, in the latrine, forming an extension of one side panel in a common plane therewith, a pair of similar half panels forming in superposed relation, the other end closure of the crate, and in the latrine forming privacy panels at opposite ends of the other side panel and perpendicular thereto, said components being provided with pre-formed matching bolt holes permitting the securing together of said components, by bolts, in either their said crate or latrine-forming relationships.

5 3. Group of correlated structural components as claimed in claim 2, said side panels and said single unit panel being each constructed with a peripheral wooden frame and an intermediate transverse member between the sides of said frame, the height of the transverse members of said single unit panel and of the side panel of which said single unit panel is an extension, in the latrine assemblage, being the same, and greater than the height of the transverse member of the other side panel, above the base of said other panel.

15 4. Group of correlated structural components as claimed in claim 2, including a dished metal liner for said bottom panel coextensive with the inside area of said bottom panel, and an outlet for said liner extending through said bottom panel.

20 5. Group of correlated structural components as claimed in claim 2, said bottom panel comprising spaced parallel skids having undercut end portions, a floor of boards secured to the upper faces of said skids, sills upon the floor at the ends thereof extending between said side panels, and a liner for said bottom panel having a dished portion coextensive with the inside area of said floor and having end portions overlying said sills, said liner having a central aperture registering with a hole in said floor.
